PREPARATION OF FIBER AND FIBER PULP

Application filed September 2, 1930. Serial No. 479,251.

My invention relates to the preparation of fiber and fiber pulp for paper, artificial board, and other fiber products, particularly from fibrous material of woody character.

5 Hitherto, mechanical wood pulp has been produced by grinding round wood on stones, and a comparatively small amount is produced by attrition mills equipped with metal plate grinding surfaces. The pulp produced by these processes is short, and does not have the maximum fibre length existing in the original wood; on the contrary, the pulp comprises fibres so short as to be known to the trade as "flour", so that it is low in freeness and strength. To make this mechanical pulp suitable for paper, it must be mixed with chemical pulps, such as sulphite, in order to get sufficient strength. Furthermore, the grinding operation commonly employed requires approximately 60 H. P. days per ton of pulp, and at least 85% of this power goes into heating the water used during the grinding operation.

I have discovered a way of producing a much better mechanical pulp with a much smaller expenditure of power. Pulp produced according to my invention can be made fibrous instead of floury, with long fibre length, good felting properties, high strength, and yet with quick draining properties or high "freeness". When stopped short at an intermediate stage, moreover, my process affords a new and advantageous method of producing a long wood fiber stock that is directly useful for many purposes without further reduction—as for the manufacture of coarse-fibered board for building, thermo-insulative, and acoustical purposes, for example.

40 In my new process, I avoid initially breaking the natural fibers of the wood into short lengths, as is done in wet-grinding as described above. On the contrary, I separate the natural fibers from one another laterally, at their natural cleavages, leaving them as long as possible,—very much longer, indeed, than it is desirable to have them in pulp for making paper. Such lateral separation of fibers may be effected in a succession of steps, first preferably by shaving off thin

slivers or bundles of fibers from a billet or piece of wood, as hereinafter described, and then by laterally tearing apart component fibers of such bundles, as in a shredding mill such as a hammer or cage mill. Only after 55 the material has thus been divided up or separated into relatively fine fibers or bundles of fibers do I subject it to treatment—as in a beater, Jordan, or attrition mill—which in further separating the component fibers also breaks them into such lengths as are ultimately desirable in pulp. In this way, the individual fibers in the final product may be made quite as fine as in the old wood flour; but their length remains much greater, because a large part of the total work of lateral separation has been accomplished without very much breakage of the ultimate fibers.

In the drawings, Fig. I is a plan view of a machine for shaving off fine slivers or fiber bundles from wooden billets,—whether round wood, slab wood, or any other suitable pieces.

Fig. II shows a fragmentary vertical section through one of the operative units of the machine, taken as indicated by the line 70 75 and arrows II—II in Fig. I.

Fig. III shows a vertical cross-section through one commercial form of shredder, of the hammer mill type, suitable for further reducing the fiber bundles from the machine 80 of Figs. I and II.

Fig. IV is a side view of a commercial form of attrition mill suitable for reducing the fiber bundles to pulp.

In the machine here illustrated, fibrous material such as wood is acted on by rapidly revolving cutters or scrapers 10 to which the wood is continually or repeatedly presented. By presenting the wood with its fibrous grain extending in the direction of the edge of a cutter 10, severance of the individual fibers is avoided or minimized, and long, thin slivers or shavings are obtained that consist of aggregates or bundles of long, unsevered fibers. The cutters 10 are preferably an inch or two longer than the billets of wood on which they act, so that slivers the full length of the billets are generally obtained. These slivers can afterward be further treated to reduce or disintegrate them to still smaller aggre-

gates or bundles of long fibers, and even, finally, to individual long fibers.

As shown in Figs. I and II, the cutters 10 are mounted on rapidly rotating cylinders 11, from whose peripheries their acutely sharpened edges project. In the present instance, there are two cutters 10, 10 to each cylinder 11, located 180 degrees apart, and removably secured in place by screws 11a. A carrier

12 slowly moves the logs or billets of wood W (Fig. II) past the cylinders 11. This carrier 12 revolves about an upright central axis at 13, and has a plurality of radially extending hoppers or pockets 14 for the billets W.

15 The cylinders 11 are arranged in a circular series concentrically with the carrier 12, and extend radially. With the revolving cylinders 11 is associated a table or shield 15 that sustains the billets W in the intervals between

20 the cylinders, and has openings 16 for the latter (Fig. II). The carrier 12 may be revolved slowly (e. g., at about 2 R. P. M.) by any suitable means, such as an electric motor 17 with reduction gearing 18 and a pinion 19 meshing with an external rack 20 on the carrier.

25 The motor 17 and gearing 18 are shown mounted on a platform or shelf 21, suitably secured and supported. The cutter cylinders 11 may be rotated rapidly (e. g., about

30 3600 R. P. M.) by any suitable means, such as individual electric motors 23, mounted around the machine as hereinafter described, and each directly connected to its corresponding cylinder 11. The slivers or shavings cut

35 from the billets W by the cutters 10 fall through the openings 16 in the table 15 into any suitable receiver (not shown). In detail, the machine may be constructed as de-

40 scribed in the concurrently filed application of Francis S. Farley, Serial No. 479,401, assigned to the assignee of this application.

In the operation of the machine, the carrier 12 is slowly rotated by the motor 17, while the cutter cylinders 11 are rapidly revolved by the motors 23. Billets of wood W are fed and dropped into the pockets 14 from the platform 21, say,—by hand or in any other suitable way. As the billets W at the bottom of each pocket 14 are pushed around on the

50 table 15 by the carrier 12, thin slivers are cut from each billet at successive tangential im- pingements with each of the rapidly rotating cutters 10, in the manner indicated in Fig. II. Since the grain of each log or billet W

55 is substantially or approximately parallel with the knife edge 10,—as well as with the axis of revolution of each cutter 10,—as the billet is presented to the cutter in this manner, the cutter divides the fibers sidewise from

60 one another, without severing them as would be the case if the billet extended crosswise of the knife edge. The smaller the path of revolution of the knife edge 10, the lower the power consumption in proportion to the quantity and fineness of slivers produced.

The projection of the cutters 10 above the table 15 controls and determines the thickness of the slivers produced, and may be varied by adjusting the height of the table.

The slivers thus obtained are long, narrow, thin wooden ribbons, about $\frac{1}{8}$ to $\frac{3}{8}$ in. wide (more or less), about $1/100$ to $\frac{1}{32}$ in. thick, and in many cases as long as the billets from which they are cut,—which may be two feet long, conveniently.

75 These slivers or bundles of laterally adherent fibers are further reduced in any suitable shredding machine that will tear the fibers apart laterally without too much transverse breakage, such as the hammer mill shown in Fig. III. Bunches or "sheaves" of the long slivers are fed in sidewise down the sloping wall 25 over the impact plate 26, where they are struck tangentially and torn to pieces by the rapidly revolving centrifugally influenced hammers 27, which are freely pivoted at 28 to their common rotary carrier 30. It will be observed that the impinging leading edges or corners of these hammers

80 27 extend in the direction of the grain of the slivers as the latter are fed in sidewise, as above described. As shown, the carrier 30 has stops 31 at either side of each hammer

85 27, to limit their swing relative thereto. The resulting strands or shreds may be carried around in the machine over the plate 26 a number of times, till they are reduced to a sufficient degree of fineness to be crowded out and discharged through the small openings of the foraminous lower wall 32, be-

90 yond the plate 26, into the receiving space there-beneath.

95 The resulting shreds or fiber bundles vary considerably in size, but lie mainly between 1 in. and $\frac{1}{4}$ in. long and $\frac{1}{2}$ in. to $\frac{1}{16}$ in. wide, and may average something like $\frac{1}{2}$ in.

100 long or more by $\frac{1}{2}$ in. wide and a couple of hundredths of an inch thick i. e., the length is generally at least sixteen times the greater transverse dimension. This long-fibered

105 stock is thus immediately suitable for use in the manufacture of coarse-fibered board, for building, thermo-insulative or acoustical purposes, etc.

110 For the manufacture of paper pulp, I further reduce these shreds or bundles of fiber, preferably by a refining operation in the nature of wet-grinding. Any suitable refining machinery may be used for this purpose,

115 such as the attrition mill shown in Fig. IV, preferably with stone linings or grinding surfaces. For this purpose, the shredded wood is first leached or soaked in water until thoroughly saturated and softened, or even

120 cooked if desired. Owing to the fineness of the shreds, they are better and more readily penetrated by the leaching liquid than are ordinary wood chips. After leaching or

125 cooking, and while still wet, they are passed through the attrition mill, being fed into the

130

hopper 35 which delivers centrally between the oppositely revolving grinding rotors 36, 37, which may be driven by belts (not shown) on pulleys 38, 39.

As here shown, the rotor 36 has an annular opening 40 from the hopper 35 therethrough, between its hub 41 and its outer portion which carries the annular grinding surface or stone lining 43. Spokes 44 across this opening 40 connect the hub 41 to the outer portion of the rotor. The rotor 37 is solid across its center, and has a grinding surface or stone lining 45 for coacting with the surface 43. Between the oppositely moving surfaces 43, 45, which are preferably grooved radially, the fine, long wet shreds are disintegrated or ground apart, mainly by lateral separation of their component fibers, but with some breakage of the fibers too. The thus ground fibers work their way outward peripherally from between the surfaces 43, 45 into the casing 46, whence they are discharged at the opening 47, in the form of a fine, moist, long-fibered pulp.

If desired, this pulp can be passed through a series of such attrition mills, so as to carry its reduction on down to any desired quality of stock, according to the purpose for which it is to be used.

Having thus described my invention, I claim:

1. A method of converting wood into long-fibered stock which comprises shaving long, narrow slivers or ribbons laterally from a billet, by successive tangential lateral impingements with a knife edge extending in the direction of the grain of the billet; and shredding these slivers into finer strands by tangential lateral impingement of hammer edges extending in the direction of the grain of the slivers, so as to tear their component fibers apart laterally, with minimum breakage of the ultimate fibers.

2. A method of converting wood into fibrous paper-pulp which comprises shaving long, narrow slivers or ribbons laterally from a billet, by successive tangential lateral impingements with a knife edge extending in the direction of the grain of the billet; shredding these slivers into finer strands by tangential lateral impingement of hammer edges extending in the direction of the grain of the slivers, so as to tear their component fibers apart laterally, with minimum breakage of the ultimate fibers; and only finally breaking the component fibers to the desired ultimate length, as an incident of the final, refining stages of reduction.

In testimony whereof, I have hereunto signed my name at Trenton, New Jersey, this 25th day of August 1930.

ROGER B. BROWN.
